ELECTRIC SIGN CONTROL MECHANISM

Filed Dec. 27, 1927

INVENTOR

Louis B. Garber
Solomon Polachek
ATTORNEY

UNITED STATES PATENT OFFICE

LOUIS B. GARBER, OF NEW YORK, N. Y.

ELECTRIC-SIGN-CONTROL MECHANISM

Application filed December 27, 1927. Serial No. 242,711.

This invention relates to an electric sign control mechanism and has for one of its objects the provision of a simple and inexpensive device for regulating the lighting of electric bulbs in a predetermined sequence.

Another object of my invention is the provision of a device for controlling the illumination of an electric sign comprising a master roller adapted to simultaneously control the 10 excitation of lamps of sign letters and lamps of a sign border.

A still further object of my invention is the provision of adjustable mechanism for controlling the illumination of an electric 15 sign adapted to be adjusted for producing different and varied effects in the sequence of intervals of illumination of the bulbs of the sign letters and the bulbs of the sign margin.

Other objects will appear hereinafter, the 20 novel features and combinations being more clearly set forth in the appended claims.

In the drawing:

Fig. 1 is a horizontal sectional view of my improved electrical sign control mechanism. 25 Fig. 2 is a longitudinal sectional view taken on the line 2—2 of Fig. 1 including a wire diagram of the electrical hook-up.

Fig. 3 is a fragmentary top plan view of a further development of my invention.

30 Fig. 4 is a fragmentary sectional end view of the form of my invention illustrated in Fig. 3.

Referring particularly to the drawing, the numeral 10 designates a casing preferably 25 comprising insulating material. A partition 11 is disposed lengthwise across the interior of the casing dividing the same into a front and rear compartment. Clock mechanism designated generally by numeral 12 of the usual construction is mounted in the rear compartment and is meshed with a gear 13 rigidly mounted on a shaft 14 which is extended transversely of the casing 10 and is 40 journaled in apertures in the rear and front walls 15 and 16, respectively thereof. Any suitable driving mechanism such as an electric motor, not shown in the drawing, may be used in place of the clock mechanism. It 45 should be understood that the clock mecha-

nism 12 is adapted to rotate the shaft 14 at a predetermined rate of speed.

A drum 17 is rigidly mounted on the shaft 14 between the partition 11 and the front wall 16. The drum 17 comprises electrical 55 conductive material and is provided with enlarged segments 18 of insulating material disposed in the periphery thereof. Shafts 19, 20, 21, 22 and 23 are rotatively mounted at their extremities in bearings 24, 25, 26, 27 and 28, respectively, which are slidably engaged in vertically disposed slots in the front wall 16 and in the partition 13. Discs 29, 30 and 31 are rigidly mounted on the shafts 19, 21 and 23 respectively, and are engaged at 60 their periphery against the periphery of the master disc or drum 17. The discs 29, 30 and 31 also comprise electrical conductive material. Grinding rollers 32 and 33 are rigidly attached to the shafts 20 and 22, respectively, 65 the grinding roller 32 being engaged against the peripheries of the discs 29 and 30 and the grinding roller 33 being engaged against the peripheries of the drum 17 and the disc 31.

It should be understood that the slidably 70 mounted bearing members in which the shafts 19, 20, 21, 22 and 23 are mounted permit the discs and grinding rollers to be held firmly in contact with each other by virtue of the tendency of the parts to move downwardly 75 under their own weight as the peripheries 80 wear.

In Fig. 2 of the drawing a wire 34 is electrically connected at one end to the shaft and drum 17 by means of a brush 35 mounted on 85 the casing 10 and engaged against the shaft 14. The other end of the wire 34 is electrically connected to one terminal of a source of electrical supply indicated at 36. A wire 37 leading from a plurality of lamps 38 of a letter of a sign which are connected in parallel, is electrically connected to the other terminal of the source of current 36. The other wire 39 of the letter battery of lamps is electrically connected by a wire 40 to the shaft 21 and the 90 disc 30, the wire 40 being attached to the bearing 26. It should be understood that the 95 above described construction is such as will permit an electric circuit through the lamps of the letters of the sign to be intermittently 100

closed and opened as the disc 30 alternately engages the metallic portion of the periphery of the drum 17 and the insulation material thereof.

5 The border of the sign comprises a group of lamps 41 connected in parallel between the wires 42 and 43 and a second group of lamps 44 connected in parallel between the wires 45 and 46, it being understood that the one of each of the lamps 41 of the first mentioned group is disposed between two adjacent lamps 44 of the second mentioned series. It should also be understood that any desired combination of colored lamps may be employed in the 10 two series. The wire 43 of the first mentioned group of lamps is electrically connected to the source of current 36 and the other wire 42 is electrically connected to the shaft 23 and the disc 31 by attachment to the 15 bearing 28 thereof. It should be understood that the above described construction is such as will cause the circuit through the group of lamps 41 to be closed when the periphery of the disc 31 engages the metal portion of the 20 drum 17 and to be open when the disc 31 engages the insulation material 18 thereof.

The wire 46 of the second mentioned group of lamps 44 is electrically connected to the source of current 36 and the other wire 45 of the 25 second group is electrically connected with the shaft 19 and the disc 29 by attachment to the bearing 24 thereof. When the disc 29 engages the metal portion of the periphery of the drum 17 the circuit through 30 the second group of lights 45 is closed and when the disc 29 engages the insulation of the drum 17 the circuit is open, it being understood that the disc 29 engages the metal portion of the drum 17 when the disc 31 is in 35 contact with the insulation thereof, and that the disc 31 engages the metal portion of the drum 17 when the disc 29 is in contact with the insulation of the drum. The above described arrangement is such as will alternately 40 cause excitation of the lamps of one group and of the lamps of the other group.

In the modified form of my invention illustrated in Figs. 3 and 4, the drum 17' comprises two sections 47 and 48. The periphery of the section 47 is provided with enlarged segments 18' comprising insulating material and the section 48 has a metal periphery throughout its entire circumference. The drum 17' is slidably mounted on square section 49 of the shaft 14' and is adapted to be engaged at its periphery by the peripheries of the discs 29', 30' and 31' mounted on the shafts 19', 21' and 23'. As shown in Fig. 3, the disc 30' is disposed over the right hand edge portion of the drum section 47 and the discs 31' and 29' are disposed over the left hand portion of the drum section 47. When it is desired to have all the lights of the border of the sign lighted permanently the drum 65 17' may be shifted to the right as viewed in

Fig. 4 so as to cause the periphery of the discs 29' and 31' to engage the integral metallic periphery of the drum section 48 while retaining the disc 30' in contact with the periphery of the drum section 47 so as to have the lights of the letters of the sign flashed on and off.

70 For the purpose of manually shifting the drum 17' from one position to another, a ring 50 having a groove therein is rigidly attached to the drum 17' and is engaged by a fork member 51 which is mounted in the groove. A rod 52 is attached at one extremity to the fork 51 and is slidably mounted in an aperture in the front wall 16 of the casing 10. The rod 52 extends through the aperture and is provided with a notch 53 adapted to be engaged by the spring catches 54 and 55 mounted on the outer and inner sides of the wall 16 for retaining the drum 17' in predetermined 75 positions.

80 The drum 17' may be automatically shifted from one position to another for varying the sequence of the excitation of the lamps of the border of the sign by a cam member 56 mounted on the shaft 14' having a groove 57 therein into which the upper end of the threaded projection 58 which is adjustably threaded in the block 59 mounted on the rod 52 extends. It should be understood that the projection 85 58 may be extended into the groove 57 of the cams 56 when desired by screwing the same upwardly.

90 While I have described that my invention is mainly used as a flasher, it is to be understood that I reserve the privilege to use the same as an automatic timer to start and stop the flashing of the signs and also other purposes.

100 Having thus fully shown and described an embodiment of my invention what is desired to be secured by Letters Patent of the United States is:

110 1. In a device of the class described, a drum mounted on the shaft of a driver clockwork, and consisting of a front section with alternate insulation and conductive segments completely around its periphery and a rear section completely conductive around its periphery, a plurality of conductive discs rotatively mounted and contacting with the drum, said drum being arranged for sliding on a square portion of its supporting shaft so that in one position all the said discs engage the front section of the drum and in a second they engage the rear section of the drum, the conductive portions of the drum, and the discs being arranged for connection for controlling electrical circuits including electric sign lamps, a ring with a cam groove mounted on the shaft supporting the drum, and a fork member engaged in the groove and connected for automatically moving the drum in sequence from one to the other of the stated positions.

2. In a device of the class described, a
drum mounted on the shaft of a driver clock-
work, and consisting of a front section with
alternate insulation and conductive segments
5 completely around its periphery and a rear
section completely conductive around its per-
iphery, a plurality of conductive discs rota-
tively mounted and contacting with the drum,
said drum being arranged for sliding on a
10 square portion of its supporting shaft so that
in one position all the said discs engage the
front section of the drum and in a second
they engage the rear section of the drum, the
conducting portions of the drum, and the
15 discs being arranged for connection for con-
trolling electrical circuits including electric
sign lamps, and a means for moving the drum
from one to the other of the stated positions.

20 In testimony whereof I have affixed my
signature.

LOUIS B. GARBER.
